DESIGN FOR A KNITTED LOOPED FABRIC

Jesse W. Bettmann, New York, N. Y.

Application February 26, 1938, Serial No. 75,432

Term of patent 3½ years

To all whom it may concern:

Be it known that I, Jesse W. Bettmann, a citizen of the United States of America, residing in city of New York, county of New York, and State of New York, have invented a new, original, and ornamental Design for a Knitted Looped Fabric of which the following is a specification, reference being had to the accompanying drawing, forming part thereof. The figure on the

drawing is a plan view of a knitted looped fabric showing my new design.

The design comprises a series of chains in striped formation, united with a series of widely separated loosely woven looped yarn as shown.

I claim:

The ornamental design for a knitted looped fabric substantially as shown and described.

JESSE W. BETTMANN.
